UNITED STATES PATENT OFFICE.

YORKE BURGESS, OF WASHINGTON, DISTRICT OF COLUMBIA, ASSIGNOR TO AMERICAN SIGNALLING COMPANY, A CORPORATION OF ARIZONA TERRITORY.

ELECTRIC RAILWAY SIGNAL SYSTEM.

No. 926,687.

Specification of Letters Patent.

Patented June 29, 1909.

Application filed November 5, 1908. Serial No. 461,174.

To all whom it may concern:

Be it known that I, YORKE BURGESS, a citizen of the United States, residing at Washington, in the District of Columbia, have invented a new and useful Electric Railway Signal System, of which the following is a specification.

This invention has reference to improvements in electric railway signaling systems and is designed to provide a system of circuits and signaling apparatus whereby a train standing upon a track or running in either direction has apparatus thereon so operated that the engine man is notified of the approach of other trains on the same track in either direction or of other dangerous conditions such as a siding open to the main track or a broken rail, or the presence of a hand car on the main track, or the lapping of a side tracked train or car into dangerous relation to the main track, or in fact any conditions of danger to the train under consideration while the train is still far enough remote from the dangerous point to give ample time for bringing the train to a standstill.

In accordance with the present invention the system under normal conditions works on closed circuit in which case there is displayed in each engine cab of the trains working under the system a white light, and along the line of way in each section, the system operating on an electric sectional system, there are electric circuits normally maintained in the closed condition so long as there is no train or car within the section and other normal working conditions are maintained.

The system is so constituted that should conditions dangerous to a train arise within dangerous proximity to such train then there will be displayed a characteristic signal, usually a red light, and the brakes will be applied automatically. Since the system operates under normal conditions on closed circuit then any break in any one of the circuits will cause the display of the danger signal and the application of the brakes upon a train entering the zone where the break has occurred.

The present invention contemplates the use of normally closed circuits upon an engine of a train which circuits are constantly closed except for accidental breaks in the circuits, and the arrangement is such that under normal working conditions and in the absence of dangerous conditions there is dis-

played a safety signal, usually a white light, and the brake system is electro-magnetically held in the released position without however affecting the normal operation of the brakes under the control of the engine man. Should dangerous conditions arise within such distance of the train under consideration as to become dangerous to such train, then the current within the closed circuit upon the train is so diverted as to operate the danger signal and to so weaken the electro-magnetic brake-controlling devices as to cause the application of the brakes.

The invention will be best understood from a consideration of the following detail description taken in connection with the accompanying drawings forming a part of this specification, in which drawings,

Figure 1 is a diagram of a number of successive sections of a system equipped with the present invention and showing the operation of the invention when a train is upon each of three successive sections. Fig. 2 is a diagram showing the arrangement of the invention for a turnout or side track. Fig. 3 is a diagram illustrating the operation of the invention in the case of a broken rail. Fig. 4 is a diagram showing the operation of the invention should there be a hand car or other car on the track which car is not equipped with the signal apparatus. Fig. 5 is a diagram showing the condition when a side tracked car has moved upon or so close to the main track as to be dangerous to a train upon said main track.

Referring to the drawings there are shown the two tracks 1 and 2 of a single track railway, the invention being shown in the drawings as applied only to a single track railway, but it will be understood that a double track railway may be equipped with the invention as well as a single track railway. One of the tracks, say the track 1 or rail 1 is shown as a continuous rail, this being understood as an electrically continuous rail, though not of course necessarily mechanically continuous. The rail 2 is broken up into electrically discontinuous sections, the rail being electrically continuous throughout the section and insulated as indicated at 3 from the electrically continuous rail section of the next succeeding or preceding electric section.

Extending along the line of way are two conductors 4 and 5 distinct from the rails and either of the over-head type of suitably sup-

connected together on the surface of the ground. The conductors k and l are made up of the number of sections m and n of core conductor connecting them so that the crossing point of k is in section i and the connection end of k two adjacent sections to l the other conductor and at a point intermediate in the length of l the crossing section. The arrangement is such

- that each conductor shall be located in a line with a length (one-half) of the length of a section of the other conductor and the remaining length of the conductors alternate with each other in position; so that the line conductors are made up of two sections of conductors alternately disposed with the distance between them throughout the length of the system.

connected to the middle position of the successive
titanium dioxide contacts 4 and 5 is another titanium
dioxide contact 6 from the other end of which a third
two conductors 7 and 8 terminating in contacts 9 and 10 respectively. In operation
the connection to the contact 9 or terminal 9 is a
switched device 11 which may either be constituted
as the assembly of two parallel switchable contacts
12 and 13. In this arrangement a second especially

conductor 138 to a common terminal 131. Adjacent to the contact 131 is a double electromagnet 135 and adjacent to this contact is terminal 110. It is a double electromagnet of such thickness that the two magnets 135 and 136 have no connection or connection by conductors 171 or a common connection 183 which in turn is connected to the flux coil 1. The magnet 135 and 136 control the switch devices 137 and 138 respectively each of which switch devices is connected to the connection 183. The free end of each switch device 136 is in operative relation to the contact 131 and the free end of each device 137 is in operative relation to the contact 110. The other side of each magnet 135 and 136 is connected to one side of the electromagnet 120. In the next section adjacent to the magnet 120 is a conductor 221 and the other side of the magnet 120 is connected to the conductor 221.

connected by a conductor 22 to one terminal of the switch 24, the other terminal 23 of the switch 24 is connected by a conductor 25 to the magnet 26. The side of the magnet 26 which is connected to the magnet 26 is connected to the side of the latter remote from the connection 17 and the other side of the magnet 26 is connected by a conductor 26 to the rail section 21 of the particular rail section to which the magnet 26 belongs. The switch 24 is connected by a conductor 27 to the same conductor section 21 to which the magnet 26 is connected. The conductor 26 and 27 are respectively connected at the opposite ends of said rail section 21 and at an intermediate point of this rail section the connection 28 is made between the two conductors 26 and 27 so that the source of electric current will be connected to the magnet 26.

The maggot 122, 135, 143 and 235 are all grouped at convenient points in a respective section, probably adjacent to the insular oak (35) and soft wood 29. But the maggot 122

was elaborate in its steel. The great sets of 22, 33, 50 and 72 with their conductors and connections of both the solid and the conductor type of transmission electric section of station and the lines may be easily disconnected at any point along the line or may be connected together and convenient.

One advantage in these systems is the use of standard electromagnetic apparatus in conjunction with that of the several electrostatic sources.

The engine can do two edlections in
mark 327 each, because each four-bladed
propeller has 33% torque reduction, so the
total ideals will be the third of the 11
engines or 1100 ft-lbs torque. However
with unbalance factors and load of 1
and wheels 5%, the course the in
mark 35 torque that we can add is connected
to the engine frame or by 3000
brackets engaging collecting plates
the maxes of the engine is 1100 ft-lbs
of torque in system. So it this is
the max of the engine. 3300 is occur
conducive to 40 ft-lbs but is not the best
max because from the load of 3% and the
of the engine and 1100 is connected by 11
so that it is 1100 ft-lbs by max
from the engine 3300.

indicative of any signal visual or audible for indicating safety but preferably this signal is in the form of a clear glass or white glass incandescent lamp.

Leading from the conductor 34 is a conductor 51 including a solenoid 52 and ultimately terminating at a switch arm 53 which latter constitutes or is attached to the armature of the magnet 36. In the path of the 10 switch arm 53 is a terminal or contact 54 connected by a conductor 55 to the conductor 41. Branched off from the conductor 41 is another conductor 56 connected to the conductor 51 adjacent to the switch arm 53 and 15 including a lamp 57 similar to the lamp 48 before referred to, that is it is preferably a lamp with a red bulb, but like the lamp 48 may be taken as indicative of any danger signal whether visual or audible but preferably in the form of a red lamp. Branched 20 in the conductor 51 around the solenoid 52 is another conductor 58 including a lamp 59 which in this case has a white or clear glass bulb and is to be taken as indicative of any 25 type of signal visible or audible which will indicate safety, but is like the lamp 50 preferably an incandescent lamp with a clear glass or white glass bulb.

Now let it be assumed that the normal condition of the apparatus at the stations when no trains are upon a section and no danger conditions are present is that shown at the right hand end of Fig. 3. Under such conditions each battery or current source 28 will 30 charge the magnets 25 and 15, which are in series, through the corresponding rail section 2 thence by way of the conductor 26 through the said magnets 25 and 15 and by the conductors 17 and 18 back to the rail 1. At the 35 same time the battery 28 will charge the magnet 12 of the particular station and the magnet 16 of the next adjacent station through the rail section 2 and conductor 27 by way of the switch arm 24 now held in the 40 closed position by the energized magnet 25 thence by the conductor 22 to the magnet 12 and by way of the conductor 21 to the magnet 16 of the next adjacent station, thence by the 45 respective conductors 17 and 18 to the rail 1 and back to the battery 28. Under these conditions the magnets 15, 16, 25 and 12 are all energized and their respective 50 switch levers are closed and consequently all the circuits named are closed as well as being closed on to the conductor 6 connected to the 55 respective conductors 4 or 5 as the case may be.

In Fig. 2 the conditions at a station and upon a train when there are no danger conditions along the track with the train in a section, are shown. The car axle and wheels 29 bridging the two tracks 1 and 2 short circuit the battery 28. The short circuiting of the battery 28 so weakens the current passing 60 through the magnets 25, 15 and 12 of the par-

ticular station under consideration and the magnet 16 of the preceding station, considering the train as moving toward the right as viewed in Fig. 2, that these magnets no longer retain their armatures which are retracted by usual retracting means assumed to be present in the structure shown though not there illustrated, and the circuit controlled by these several armatures are opened. However the bridging of the particular battery 28 referred to does not affect the magnet 16 of the particular station, this magnet being still energized by the next succeeding battery 28. The dynamos 30 and 31 are assumed to be constantly running and generating current. Under the conditions assumed the circuit of the dynamo 30 is through the shoe 33 to the conductor 5 thence by the respective conductor 6 of the next preceding station, thence by way of the conductor 7 75 and terminal 9 to the switch arm 11 which under these conditions is closed upon the terminal 9 since the magnet 12 is energized, thence by the conductor 13 to the terminal 14 and by way of the switch arm 19 to the conductor 18 and rail 1, returning to the dynamo by way of the axle and wheels 29 and the conductors 39 and 38 to the magnet 36 and back to the other brush of the dynamo by way of the conductor 40. Under these 80 conditions the magnet 36 is energized and its armature lever 44 is held closed on to the contact 45. There is thus maintained a circuit from the dynamo 30 through the conductor 42, solenoid 43 and lamp 50 in multiple 85 and thence by way of the switch lever 44 and conductor 46 back to the other side of the dynamo, the said lever 44 and conductor 46 providing a low resistance branch about the lamp 48. The lamp 50 and solenoid 43 90 are so proportioned that the current from the dynamo 30 will flow through these two elements in multiple and light up the lamp 50 to brilliancy and at the same time charge the solenoid 43 to the fullest intended 95 capacity. Under these conditions the lamp 50 glowing denotes a safety condition of the entire apparatus within a safety zone of the particular engine and train under consideration. At the same time the energization of the solenoid 43 is made to control the brake system in such manner that the brakes will not be applied except at the volition of the engine man, the conditions being such that when the solenoid 43 is deenergized the emergency side of the air brake system is made active and the brakes are then automatically 100 applied.

At the right hand end of Fig. 2 there is shown a turn-out or switch 60 which may be taken as of the ordinary conventional form. An arm 61 leading from the switch target is provided with a bridging contact 62 arranged to open or close the circuit between 105 two terminals 63 in branches 64 of the adj-

cent conductor 18 of the station toward the approaching train.

When the turn-out switch is in a position whereby the siding is cut out from the main track and it is safe for trains to travel on the main track without danger of being shunted into the siding then the closure of the conductor 18 through its branches 64 maintains the conditions of safety at the adjacent station. But suppose the switch should be turned into a position to connect the main track with the siding then the bridging contact 62 is moved out of electrical connection with the terminals 63 and the conductor 18 has its continuity broken through the branches 64. Now the magnet 16 has its circuit broken and is therefore no longer charged and its armature lever moves away from the contact 10 and the electrical connections of the conductor 6 to the track 1 are broken.

While the shunting switch 60 was in the position to maintain the main track intact the circuit between the conductor 6 and track 1 was closed and consequently the current from the dynamo 31 energized the magnet 37 and the solenoid 52 and lamp 59 remained in the charged position the same as the local controlled by the dynamo 30. Now however, considering that the shunting switch 60 is closed on to the main track so that the track is connected to the siding then the circuit through the conductor 6 is broken and the magnet 37 is no longer energized so that its armature lever 53 will move away from the contact or terminal 54 thus breaking the shunt circuit about the lamp 57. Now the current from the dynamo 31 has its path defined by the conductor 51 through the lamp 59 and solenoid 52 in multiple arc and back through the conductor including the lamp 57 in series with the multiple arc branches including the solenoid 52 and lamp 59. Under these conditions enough current will pass through the lamp 57 to cause the same to glow brightly, but the current dividing between the lamp 59 and solenoid 52 will fail to energize either of these two elements operatively and consequently the lamp 59 will dim down or actually cease to glow entirely while the solenoid 52 will become so weakened as to no longer be operative.

The going out of the white lamp and the flashing up of the red lamp together with the application of the brakes of course indicates the presence of a dangerous condition within the dangerous proximity and of course if such conditions prevail for any length of time a proper one of the train crew will make an investigation so that the dangerous condition may be remedied if possible or such measures of relief be taken as may be necessary.

In Fig. 1 there are shown three trains upon three successive sections. Let it be sup-

posed that the middle train of the three has broken down or become otherwise stalled upon the section, then another train entering the section immediately to the left will become affected by the stalled train and be brought to a standstill while the signal device indicating trouble ahead of the train will be energized so that the red lamp will glow and the same conditions will become present in that portion of the signal device on the stalled train toward the approaching train. If also a train be traveling toward the left as viewed in Fig. 1 and comes upon the section immediately adjacent to the section occupied by the stalled train, then its signal device indicating danger will be energized on the side toward the stalled train and the approaching train will be brought to a standstill while the engine man on the stalled train will be apprised of the fact by the operation of his signal device on the side toward the last named approaching train indicating a dangerous condition on that side of the stalled train occupied by the last named approaching train.

Let it be supposed that from some cause or other there should be a broken rail in the track as indicated at 65 in Fig. 3, it being immaterial whether this broken rail be in the track 1 or track 2. This has the same effect as bridging a battery 28 by the presence of a train in the section where the break occurred and as soon as the train enters the next succeeding section in a direction traveling toward the track break 65 then the danger side of the train carried mechanism is energized and the train is brought to a standstill. Of course the engine man does not know what the danger condition may be and after a proper time interval investigation will be set up and the broken rail be found and may be repaired after which the danger conditions being relieved the magnet 36 or 37 of the train-carried apparatus will again become energized and the safety signal once more displayed and the brakes released so that the train may proceed.

Suppose that a hand car should be upon a section or a car or train unequipped with signal devices should be upon a section. Such a condition is shown in Fig. 4 where a hand car or other car unequipped with safety devices is indicated at 66, the showing in the figure being that of a pair of wheels and connecting axle as sufficiently indicative of such an unequipped car or cars and the structure 66 has been shaded simply to distinguish it from the structure 29 which latter is to be understood as indicating a locomotive equipped with the safety devices. Since the car 66 will bridge the rails 1 and 2 it will act the same as though a train equipped with safety devices was present in the section, and consequently an approaching train indicated diagrammatically in Fig. 4, will on entering the

next section to the car 66 in a direction approaching the same be notified of the presence of some dangerous condition and be brought to a standstill as under other dangerous conditions and upon investigation the dangerous condition may be avoided, though in the case of a moving car unequipped with safety devices, as for instance a hand car, the danger conditions may be removed by the traveling of the car out of the section if it be going in the same direction as the train. If the hand car be going toward the train, of course it may be readily stopped before any accident has occurred.

Another condition is shown in Fig. 5. Sometimes cars which have been shunted on a siding will move or be moved therefrom either wholly or partially onto the main track either through accident, or carelessness or maliciousness, and thereby become a menace to a train moving on the main track. Or sometimes a car shunted on a siding may not be moved quite far enough thereon and be unintentionally left in a position where it may side swipe a train passing on the main track. In Fig. 5 there is shown a means for preventing such an accident by providing at such a turn-out two electro magnets 15' and 16' controlling armatures 19' and 20' respectively arranged to either of them close the circuit of a conductor 6' leading to a sectional conductor 4 or 5 as the case may be. One side of the magnets 15' and 16' has a common connection to the track rail 1 by a conductor 18 and the armatures 19' and 20' have also a common connection to the track 1 by the common conductor 18. The magnet 16' is connected by the conductor 21 to the magnet 12 of a preceding or adjacent station, while the other side of the magnet 15' is connected by a conductor 27' to a section 2 of the main track and also of the siding while the other side of the siding is connected by a conductor 67 to the track 1. If now a car such as indicated at 68 which had been shunted on the siding should move on to a section 69 of the siding immediately adjacent to the shunting switch then there is established a circuit from the battery 28 beyond the shunting track switch through the wheels and axles of the car 68 and by the conductor 67 to the track 1 and back to the battery. Under ordinary circumstances the magnet 15' is charged by the battery 28 referred to and its armature 19' is attracted thus closing the circuit through the conductor 6' to the track rail 1, but when the car 68 short circuits the battery 28 then the magnet 15' is deenergized and its armature 19' moves away therefrom and opens the circuit to the conductor 6' previously closed by said switch 19'. When a train enters on the section next adjacent to the shunting switch upon which the car 68 has moved to an extent to be a menace to a train moving on the main

track then the magnet 16' is deenergized in the same manner as the magnet 16 of an adjacent section is deenergized when a train enters a section. This completely breaks the circuit through the conductor 6' and consequently the danger signal is displayed in the cab of the approaching train and the brakes are applied in the manner already described, the danger signal being displayed on the side of the cab toward the danger point. In the case of an open draw-bridge the conditions would be similar to the switch shown in Fig. 2 and a similar arrangement would be provided.

From the foregoing it will be seen that all the several structures along the line of way are maintained on normally closed circuits and on the entrance of a train into a section certain of these circuits are opened but not all. On the train the circuits are of two characters one local to the train and the other through the sectional line conductors and the track. Under normal conditions the combined train and track and sectional line circuits remain intact so that the sources of current on the train cause the maintenance of safety conditions. In the circuits local to the train however, the current is always flowing whether the external conditions be safety or danger, but the amount of current flowing through the safety or danger element is so modified by safety or danger conditions that these elements are operated accordingly.

Should a break occur in any of the line circuits from any cause a danger signal will be displayed and the train brought to a standstill. Should the white light go out without the application of all of the brakes or the display of the red signal, then it would indicate a break in the signal immediately local to the safety lamp. Since such a break in the circuit is usually due to the rupturing of the filament of the lamp the introduction of a new lamp will cure the trouble. Should the brakes be applied without the display of the red signal then it is an indication that a danger zone has been entered but the filament of the red lamp or the immediate circuit of said lamp has become broken and as this fault is usually in the filament of the lamp the introduction of a new red lamp will cure the trouble.

It is to be observed that in the present system the polar relation of the current sources on the train or along the line of way to the direction of travel of the train is immaterial.

What is claimed is:—

1. In an electrically operated railway signal system, section stations along the line of way connected one to the other and having normally closed charged circuits including circuit-controlling devices, alternately crossing sectional line conductors having circuit connections controlled by the circuit-con-

trolling devices at the said stations, a constantly closed train-carried circuit including a train-carried source of current and signal means, and means on the train including a circuit-controlling means for including the train-carried current source in those section station circuits the continuity of which are intact.

2. In an electrically operated railway signal system, section stations along the line of way connected one to the other and having normally closed charged circuits including circuit-controlling devices, alternately crossing sectional line conductors having circuit connections controlled by the circuit-controlling devices at the said stations, a constantly closed train-carried circuit including a train-carried source of current, signal means in said constantly closed circuit, and means on the train including a circuit-controlling means for including the train-carried current source in those section station circuits the continuity of which are intact and for controlling the flow of current to the train-carried signal means in accordance with predetermined circuit conditions.

3. In an electric-section signal system, alternately crossing sectional line conductors, other sectional conductors and a continuous conductor along the line of way, a source of electric energy in each section bridging the continuous conductor and the section of the second named sectional conductor, two electro-magnets at each section station, the first connected to the continuous conductor and the second to the adjacent section of the second named sectional conductor, circuit controllers at each section station, one actuated by one of the magnets and another by the other of the magnets, a circuit leading from one of the circuit controllers to the next adjacent section station on one side, a third electro magnet at the section station, a circuit including the same coming from the next adjacent section station on the other side, a circuit controlling means acted on by the last named electro magnet, and means including the circuit controlling means under the influence of the second and third electro magnets for coupling the respective one of the alternating crossing sectional conductors to the continuous conductor.

4. In an electric-section signal system, alternately crossing sectional line conductors, other sectional conductors and a continuous conductor along the line of way, a source of electric energy in each section bridging the continuous conductor and the section of the second named sectional conductor, two electro-magnets at each section station, the first connected to the continuous conductor and the second to the adjacent section of the second named sectional conductor, circuit controllers at each section station, one actuated

by one of the magnets and another by the other of the magnets, a circuit leading from one of the circuit controllers to the next adjacent section station on one side, a third electro magnet at the section station, a circuit including the same coming from the next adjacent section station on the other side, a circuit controlling means acted on by the last named electro magnet, and means including the circuit controlling means under the influence of the second and third electro magnets for coupling the respective one of the alternating crossing sectional conductors to the continuous conductor, and a train-carried means comprising two sources of electrical energy, current conducting means leading from each current source to the alternating crossing conductors, other current conductors each including a circuit controller and leading to the continuous conductor, and constantly closed signal circuits fed individually by the current sources on the train and containing differentiated signals, said constantly closed signal circuits receiving current from the current sources on the train in accordance with the circuit conditions along the line of way.

5. In an electric section signal system for railways, train-carried signal means comprising a closed charged circuit having differentiated signal devices responsive to the current flowing in the circuit, said closed charged circuit being local to the train, and means for causing the operation of one only of the signal devices at a time without breaking the closed circuit.

6. In an electric section signal system for railways, train-carried signal means comprising a closed charged circuit, electrically operated safety and danger indicating signals both fed simultaneously and continuously from the current source in the closed circuit, and means for causing an operative flow of current through either but not both signal means at one time.

7. In an electric section signal system for railways, train-carried signal means comprising a closed charged circuit, electrically operated safety-signal and brake-controlling means in multiple arc relation in said closed circuit, an electrically operated danger signal means in said closed circuit in series with the safety-signal and brake-controlling means, and means for shunting the danger-signal means without breaking said closed circuit.

In testimony that I claim the foregoing as my own, I have hereto affixed my signature in the presence of two witnesses.
